SHELF ATTACHING AND SUPPORTING
MEANS

Thomas M. Dunham, Batavia, Ill., assignor to
Aurora Equipment Company, Aurora, Ill., a cor-
poration of Illinois

Application April 17, 1946, Serial No. 662,847

3 Claims. (Cl. 211—147)

1

This invention relates to shelf attaching and supporting means, and more particularly to means cooperating with the shelf and support therefor to fixedly position and support the shelf.

In accordance with the principles of my invention, I provide a shelf supporting member, which may be a case, cabinet, or the like, or merely end walls or corner uprights having horizontally aligned sets of openings therein at various levels, and attaching means for insertions in the registering opening portions. The openings in the shelf supporting members are in the general shape of a key-hole, in that they have an upper portion defined by arcuate shaped margins, and the margins of the lower portion of each opening are convergent downwardly to effect frictional engagement with the shank of the fastening means. The latter may comprise screw machine parts having circular heads joined by a cylindrical shank. One of the heads is sufficiently small to be insertable through the upper portion of the key-hole shaped opening but larger than the space between the converging margins, while the other head is sufficiently large to prevent its passage through a corresponding opening in the shelf.

An attaching means for securing two or more shelf supporting units, substantially as hereinbefore described and complete per se, in parallel spaced relation and interconnected successively, may comprise screw machine parts having circular heads joined by a generally cylindrical shank whose center portion is of like diameter to the smaller of the heads and sufficiently small to be insertable through the upper portions of key-hole shaped openings in the shelf supporting member but larger than the space between the converging margins defining the lower portions of the key-hole shaped openings. The shank of said attaching means tapers at each end to define identical generally cylindrical necks connecting the shank and circular heads. These necks effect a gripping frictional engagement with the downwardly converging margins of the key-hole shaped openings, and when these openings are in registration the attaching means will secure the shelfed units in parallel spaced relation.

It is therefore an important object of this invention to provide a simple yet rugged shelf attaching and supporting means for fixedly but removably positioning a shelf in supported relation to a supporting member, such as the end walls of a cabinet, case, corner uprights or the like.

2

It is a further important object of this invention to provide shelf attaching and supporting means of novel and improved construction that enable a shelf to be changed from one position to another in relation to the shelf supporting member with a minimum of effort and a maximum of safety.

Another important object of this invention is to provide shelf attaching and supporting means that enable complete shelfed units to be firmly interconnected.

On the drawings:

Figure 1 is a broken perspective view of a case, cabinet or the like; embodying shelf attaching and supporting means of my invention, with the openings on the supporting members omitted;

Figure 2 is an enlarged side elevational view of an attaching and interconnecting means for holding one shelfed unit to another adjacent unit;

Figure 3 is an enlarged side elevational view of a shelf supporting and attaching means according to my invention;

Figure 4 is an enlarged fragmentary sectional view showing the attaching means of Figure 2 connecting two shelf supporting units, such as two of the units shown in Figure 1;

Figure 5 is a fragmentary sectional view of the shelf supporting member of Figure 3 shown in shelf supporting position;

Figure 6 is an enlarged fragmentary end elevational view of a corner upright;

Figure 7 is a sectional view taken along the broken line VII—VII of Figure 6; and

Figure 8 is a fragmentary sectional view taken along the line VIII—VIII of Figure 5 showing the shelf supporting member of Figure 3 inserted into the key-hole shaped slot and dotted in cammed position.

As shown on the drawings:

The reference numeral 10 indicates generally a shelfed unit, such as may be used for a storage bin for metal parts. Said shelfed unit comprises four corner upright support standards 11, 12, 13 and 14, positioned by pairs, in parallel planes. Since all the support members are identical, except for being right or left hand, only one of them need be described. The upright member 12, for instance, is of suitably heavy metal bent right-angularly to define a narrow flange 15 provided with apertures 36 (as by punching) on equally spaced centers providing for attachment thereto by nut, bolt or rivet, of support braces such as the support brace 16. Said standard 12 is rigidly

secured, by bolt or rivet, at the upper end to a downturned flange 17 of a top cover 18 and rigidly secured in similar fashion to a downturned flange 19 of a lower shelf 20. The broad face of the standard 12 is apertured, as at 36a, adjacent the outer portion, that is, the edge away from the right angular bend, on equally spaced centers, which outer portion is slightly recessed inwardly, as at 40. Apertures 36a serve for attaching sway braces, similar to support braces 16a (Figure 1), or end panels, as by means of nuts, and bolts, or rivets, to more securely position the corner upright standards 11 and 12, and 13 and 14 in parallel planes.

Said support standard 12 is provided with key-hole shaped openings 21, the upper portion of which is generally circular and the lower portion defined by opposed, downwardly converging marginal edges 22 and 23.

A plurality of shelves, similar to the identical shelves 20 and 24 and top cover 18, may be mounted between the support standards 11, 12, 13 and 14. Said shelves may all be identical in size and shape so that only one need be described. The shelf 24, for instance, is provided with downwardly turned flanges 19a. The lower edge of each flange, such as the flange 19a, may be turned back upon itself, or rolled, to provide a strengthening and rigidifying member 38. Each of the shelf flanges, such as the shelf flange 19a, is provided adjacent its ends with an opening 39 that may suitably be of the same diameter as the upper circular portion of the key-hole shaped opening 21.

A fastening member, indicated as a whole by reference numeral 25 (Figure 3), is used for fastening the shelf 24 in place. Said fastening member 25 comprises a stud having a head 26 that is smaller in diameter than the circular opening 39 and the corresponding circular upper portion 27 of the key-hole shaped opening 21, but larger in diameter than the distance between the spaced marginal edges 22 and 23, and a second head 28 that is larger than said circular opening 39. An intermediate shank 29 connects to the head 28 at one end and has an upwardly tapering portion 41 connecting the head 26 at the opposite end, is cylindrical in shape and of a diameter greater than the minimum distance between the spaced marginal edges 22 and 23 but less than the maximum distance between said spaced marginal edges.

In fastening a shelf 24 in place, the shelf is adjusted to a height at which the circular opening 39 will register with the circular upper portion of the key-hole shaped opening 21, and the head 26 of a fastening member 25 is then inserted through the registering openings. The shelf is then moved downwardly to effect frictional gripping engagement between the shank portion 29 of the fastening member 25 and the converging marginal edges 22 and 23. Said marginal edges 22 and 23 thus effect a camming action with the shank 29 (shown in dotted lines in Figure 8), and as the weight to be supported is placed on the shelf, the frictional engagement becomes tighter and more rigidly fastened to the shelf supporting member.

The fastening member 25 may suitably be a screw machine part, formed of steel. The heads 26 and 28 are separated by a distance approximately equal to the combined thickness of the wall of the upright member 12 and the wall of the downturned flange formed on the shelf 24. A portion of the thickness of the shelf support-

ing member rests on the tapered end 41 of the shank 29 effecting a wedging action bringing the shelf 24 and the shelf supporting member 12 into tighter association, thereby adding to the rigidity of the shelved unit 10.

In order to remove a shelf, or to change its position, it is merely necessary to give each of the attaching means 25 a light tap in an upward direction with a hammer or other object to free the shank 29 of attaching means 25 from its cammed engagement with the converging margins 22 and 23. The shelf is then raised to a point where the head 26 of the attaching means 25 may be removed through the registering opening from the inside, leaving the shelf unattached to the shelf supporting member 10 and ready to be moved into an adjusted position or to be removed entirely.

Shelved units, as the unit 10 illustrated in Figure 1, may be securely interconnected by a fastening member, indicated as a whole by reference numeral 30 (Figure 2). Said fastening member 30 comprises a stud having a head 31 identical to previously described fastening member head 26, and a second head 32 identical with the head 28 of fastening member 25. A cylindrical shank 33 of a like diameter to the head 31 tapers downward at each end 42 and 43 to define identical necks 34 and 35 connecting the said shank to the respective heads 31 and 32. Said necks 34 and 35 are cylindrical in shape and of a diameter greater than the minimum distance between spaced marginal edges 22 and 23 but less than the maximum distance between said spaced marginal edges.

In fastening shelved units, the units are brought into spaced relation and positioned so that corresponding key-hole shaped openings, similar to the key-hole openings 21 in the support standards 12 and 37, which are identical with support standards 11, 13 and 14, will oppose each other. The head 31 is then inserted through the registering openings so that the necks 34 and 35 are located immediately above the maximum distance between the spaced marginal edges 22 and 23. Fastening member 30 is then moved downwardly to effect frictional gripping engagement between the necks 34 and 35 of the fastening member 30 and the converging margins of the corresponding key-hole shaped openings, effecting a camming action. A portion of the thickness of each of the support standards 12 and 37 rests on the tapered ends 42 and 43 of the attaching member shank 33 effecting a wedging action that assists in rigidly inter-securing the shelved units 10. Said fastening member 30 may be a screw machine part, formed of mild steel.

As two corresponding support standards of the shelved units to be interconnected will oppose each other in spaced relation, a minimum of two of said fastening members 30 must be used, and it is desirable to employ six so that the shelved units are then rigidly attached together and are separated by the distance represented by the length of the shank 33 of the fastening member 30. Thus by utilizing fastening members 30 and repeating the attaching procedure, an indefinite number of shelved units may be successively fixedly fastened together forming a bank of parallel shelving for use as desired.

It is thus apparent that I have provided simple yet rugged shelf attaching and supporting means, the use of which greatly facilitates the setting up of shelves in cases, cabinets or between corner rack uprights or the like. The provision of such attaching means in combina-

tion with the construction of the shelf supporting means that has been described herein makes it a simple matter to vary the spacing of adjacent shelves to accommodate the particular objects to be stored. Also, apparent, is the simple yet effective attaching means, the use of which greatly expedites a practical rigid inter-attachment of complete shelved units in parallel to allow a wider range of utility when employed as storage space.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In combination, shelving units each having shelf supporting members provided with aligned sets of spaced key-hole shaped openings capable of inter-registration, each opening having an arcuate upper portion and a lower portion defined by converging margins, a generally cylindrical attaching means comprising spaced circular heads of different sizes, the smaller of said heads being of a diameter greater than the maximum distance between converging margins of said openings and of lesser diameter than the arcuate portion, the larger of said heads having a larger diameter than said openings, said heads being connected by a generally cylindrical shank tapering downward at each end to define identical necks of greater diameter than the minimum distance between converging margins of said openings and of less diameter than the maximum distance between said converging margins, said attaching means being capable of insertion into said registered openings in said supporting members to fixedly position said shelving units by frictional engagement as said necks cam downward between said converging margins of said openings.

2. In combination, shelving units each having shelf-supporting members provided with aligned sets of spaced key-hole shaped openings having converging margins and capable of inter-registration, and attaching means insertable into registered openings in said shelf-supporting members to fixedly position said shelving units

5 in spaced relation by friction camming engagement with said converging margins of said key-hole shaped openings, each of said attaching means having spaced heads of unequal size and an intermediate shank portion having spaced frusto-conical oppositely directed tapered portions adjacent said heads, respectively, for frictional camming engagement with the margins of said openings, said attaching means including 10 reduced diameter necks between the tapered portions and the heads.

3. In combination, shelving units each having shelf-supporting members provided with key-hole shaped openings, each opening having an arcuate upper portion and a lower portion defined by converging margins, and attaching means comprising circular heads of unequal size and an intermediate shank connecting said heads, said shank tapering downwardly and outwardly at each end to define oppositely directed frusto-conical tapered portions and including reduced diameter necks between the tapered portions and the heads, said shank being capable of insertion into registered key-hole shaped openings in said shelf-supporting members with said frusto-conical tapered portions in tightly fitting camming engagement with said converging margins to fixedly position said shelving units in spaced relation.

30 20 25 30 35 40 45 50 THOMAS M. DUNHAM.
